UNITED STATES PATENT OFFICE.

GERALD G. BARRY, OF CHICAGO, ILLINOIS.

METAL WHEEL.

Application filed August 15, 1921. Serial No. 492,348.

To all whom it may concern:

Be it known that I, GERALD G. BARRY, a citizen of the United States, and a resident of Chicago, in the county of Cook and State 5 of Illinois, have invented certain new and useful Improvements in Metal Wheels, of which invention the following is a specification.

The present invention relates principally, 10 but not exclusively, to wheels for automobiles wherein the supporting structure between the hub and rim members is formed from sheet metal. The per pound capacity of a relatively thin sheet metal plate when 15 placed on edge to withstand enormous load strains is well known, but in vehicle wheels the danger from the severe twisting or lateral strains in striking curbing, ruts or other obstructions, is an important one to be 20 guarded against. The ordinary disc wheels frequently "buckle" or become distorted; and difficulty is also found at the fastening of the thin wall to the hub. The object of 25 my invention is to overcome these practical conditions and to provide a wheel which is light in weight, yet capable of withstanding severe driving stresses, is of pleasing appearance, simple and low in cost of construction, and has other advantages which will be apparent to the manufacturer and users of 30 such wheels.

In the accompanying drawings, forming 35 part of this specification, like letters or marks of reference are used to designate 40 similar parts throughout the several figures.

Fig. 1 is a side elevation of the new wheel, 45 a portion being broken away to expose details for explanatory reference; Fig. 2 is a transverse view taken on the arrowed line 2-2 of Fig. 1; Fig. 3 is a detail cross-section, through one unit and parts of adjacent units, as indicated by the arrows 3-3 of 50 Fig. 1; Fig. 4 is another transverse section showing a modified form of rim assembly; and Fig. 5 is a detached view of one of the 55 sector-shaped supporting units.

The hub member, generally speaking, is 60 designated by A. The hub in connection with which the new structure is here illustrated is a front wheel hub, having suitable openings to receive the customary bearings, shaft, etc. Of course, any other suitable hub or shaft member may be employed. In the hub shown a^1 is the main hub body, a^2 denotes the customary integral flange extending 65 outwardly from and following circum-

ferentially around the inner end of the main hub body; a^3 is a removable cap or clamping member, having interior threaded portion a^4 for screwing upon the outer threaded 70 end a^5 of the hub body a^1 . The operation of this particular hub member will be referred to later.

Element B, the new supporting structure between the hub A and outer rim member C, 75 will now be described. The main body is composed of a plurality of sector shaped units, each preferably drawn from one piece of sheet steel, the wheel illustrated in Fig. 1 showing this supporting structure made up of 80 ten such sector units. In a co-pending application, Serial No. 415,511, I show somewhat similar sector supporting units consisting of two complementary members, telescoped together, and the present design embodies features of improvement upon the structure 85 there shown. Referring more particularly to Fig. 5 and the broken and exposed part of Fig. 1, these hollow sector units are preferably drawn, by a suitable series of operations, from a single piece of sheet or blank, so as to form as a seamless one piece unit the inner or hub base portion b^1 , the spaced apart side walls, marked b^2 and b^3 , tapering 90 from the hub toward the rim, and connecting walls b^4 and b^5 . The outer or rim end, marked b^6 , is open to permit withdrawal of the male plug of the forming die. The edge is suitably trimmed to conform to the rim. Into this open outer end b^6 of each unit, however, there is preferably then inserted a snugly fitting "felly" section, preferably 95 having a base b^7 and outwardly drawn integral flange b^8 extending around and closing the end b^6 of the unit. It will be observed that the taper given by the walls b^4 and b^5 allows a good wedging action to this closure, and if desired the units may be 100 dipped in solder or otherwise more certainly sealed against the admission of water etc.

Before placing the outer closure, however, I prefer to insert a suitably formed reinforcement b^9 down inside at the hub end, which may be secured in place by then pressing, but not piercing, a part of the walls b^2 105 and b^3 as indicated at b^{10} .

In drawing the units, the inner or hub end of the walls b^4 and b^5 is given a less or practically no taper, as indicated at b^{11} , and when the series of sector units are assembled, 110 as shown in Fig. 1, there is thus provided between adjacent units a suitable opening

through which securing bolts or rivets b^{12} may be passed. In assembling the series of units B, I prefer to provide at the center, on opposite sides, a pair of flat circular reinforcing plates, marked b^{13} and b^{14} , preferably of a heavier gauge of sheet steel, and the series of units B are clamped tightly between these plates by the bolts or rivets b^{12} . These members b^{13} , b^{14} , of course, have a central opening, permitting mounting upon and removal from the hub. At the outer edge, the adjacent units may be riveted or otherwise secured together at the adjoining "felly" section ends, as indicated at b^{15} .

If thus clamped and secured, the series of units would form a quite rigid wheel, adapted to be mounted upon any suitable hub, and to have operatively mounted and supporting thereupon any suitable form of tire carrying rim C.

In Fig. 2 and Fig. 1 a tire carrying rim is shown which embodies my preference for straight side pneumatic tires. This consists of an annular band c^1 , provided with an inwardly extended integral flange c^2 . The supporting structure B, assembled as just described, may be forced within the band c^1 and against the flange c^2 ; or the more permanent joining of the units, as at b^{15} , may be omitted, and the series of units merely placed within this outer rim structure to make the assembled wheel form of the structure. On the inside of the wheel is a detachable annular flange c^3 , and the series of supporting sector units may be clamped permanently in place by a series of rivets c^4 , extending from the flange c^3 through the wall b^8 , the opposite flange wall of the "felly" section, the wall b^2 and the rim flange c^2 but not through the detachable part of the rim structure to be presently referred to.

On the inner edge of the band c^1 is an outwardly extending integral flange c^5 (see Fig. 2 and Fig. 1); and at the opposite side is a corresponding, but detachable, flange c^6 , the latter having a further integral part c^7 extending hubwardly and adapted to abut the flange c^2 . This removable side c^6 , c^7 is detachably secured by a series of bolts c^8 , the inner end of which may be provided with a suitable head c^9 adapted to prevent turning when the lugs or nuts c^{10} are turned upon the threads c^{11} provided on the outer ends of the bolts c^8 .

In Fig. 4 is illustrated a transverse section through a further form of rim assembly. The band c^1 is provided with integral "clincher" type of tire retaining flanges, which for distinction from the "straight" side type shown in Fig. 2, are here marked c^{12} and c^{13} . This is the type generally used on the well known Ford car. This rim may be permanently secured to the series of sector supporting units by providing the

outwardly extending flanges b^8 with further flanges on opposite sides, marked b^{16} and b^{17} ; the assembled series of which will form an annular band which is forced within the rim band c^1 . On the outer side, at least, of the wheel I prefer to also provide an annular angle flange member, one part b^{18} conforming to the annular flange b^{17} and the other, b^{19} fitting against the wall of the supporting units. Obviously a corresponding angle flange piece may be provided on the opposite side of the wheel. The whole may be secured to the rim band c^1 by rivets b^{20} and cross rivets b^{21} .

The before described supporting structure, provided with a suitable hub receiving central opening, obviously may be mounted upon any form of hub. I have here illustrated a special form of hub. In Fig. 1 and Fig. 2, it will be noticed the main hub body a^1 is made non-circular, and is also tapered from the flange a^2 toward the outer edge. The ends b^1 of the respective sector units and the clamping flanges b^{13} , b^{14} of the supporting structure are shaped and tapered to correspond; and I also contemplate inserting a corresponding shaped ferrule in the structure B. This form of hub and complementary hub receiving opening on the supporting structure B is adapted to permit easy positioning or removal of the supporting structure, and when in place the non-circular shape affords the driving means. I also contemplate co-operating means between the flange a^2 and flange b^{13} for assisting in driving. On the outer end of the hub body a^1 is the threaded portion a^5 coacting with the threaded part a^4 of what might be termed the "wedging" cap a^3 . It will be observed from Fig. 2 that as this cap is screwed upon the end a^5 the supporting structure B is forced upon the body a^1 and tightly against the inner flange a^2 ; and when the cap a^3 is unscrewed and removed the supporting structure may be readily demounted from the hub. To prevent the cap from becoming unintentionally unscrewed I lock the same in position by means of a small spring pressed plunger fitted in the outer edge of the flange cap a^3 , which engages with one of a series of holes bored in a circular line around the face of the clamping flange b^{14} . The plunger a^6 may be held out of place when screwing or unscrewing the cap, but when released the flange a^3 will only need to be moved a very small fraction of a turn when the plunger will snap into one of the holes and further movement prevented.

The tightly abutting relation of the series of sector shaped units forming the main supporting structure should be carefully noted in the several figures of the drawings. These sector shaped hollow metal units reinforce and brace each other. It will be observed

there is thus provided in the assembled wheel, in effect, a pair of "discs", spaced apart, under and supporting the rim member, the spaced apart walls b^2 , b^3 , being 5 braced against side strains by the series of connecting walls b^4 , b^5 , which also serve as a radial two-ply "spokes" to supplement the "discs" b^2 and b^3 in supporting the rim C upon the hub member A. The series of 10 "felly" sections, preferably inserted and closing the end b^6 , when assembled thus form a strong support, like a felly. In an other view of the subject, the support structure B may be regarded as consisting of a 15 solid series of sector shaped hollow spokes, secured much like an ordinary spoke.

One of the main drawbacks found with so-called disc wheels on automobiles is the difficulty of fastening to the hub flange and 20 the danger of buckling. As a result a heavier gauge of metal is used than is required for the normal load, and frequently a specially formed blank, thicker at the hub fastening than toward the rim is employed. It will be apparent that by my 25 design with the use of a relatively thin and light weight standard sheet, a wheel structure, constructed and assembled as herein described, will have the capacity to withstand 30 severe side-thrust as well as other driving stresses, and the advantages of its hub fastening over the ordinary disc wheel should be obvious. The series of sector units furnish a wide foundation similar to 35 and are fastened like the ordinary wooden spoke artillery wheel.

It will be apparent that various changes may be made in the wheel herein chosen for illustration without departing from the 40 spirit and scope of the invention, and I do not wish any undue limitation to result from the detailed description given, but desire the claims appended hereto to be construed as broadly as possible in view of the prior 45 art relating to such wheels.

What I claim as new and desire to secure by Letters Patent is the following:

1. In a wheel, included as a support between the hub and rim members, a series 50 of sector shaped hollow metal units formed in a single piece, arranged in abutting relation with each other, and constructed and assembled substantially as shown and described.
2. In a wheel of the character described, 55 the hollow metal units, each comprising a sector of the supporting structure between the hub and rim members, formed from a

single metal blank, substantially as shown and described.

3. In a wheel of the character described, 60 the hollow metal units, each comprising a sector of the supporting structure between the hub and rim members of the wheel, formed from a single metal blank substantially as described herein, and inserted in each unit a felly section reinforcement and closure, substantially as set forth.

4. In a wheel of the character described, 65 as a supporting body between the hub and rim members, a plurality of hollow metal units, each drawn from a single blank so as to provide integrally the base b^1 , the two sector shaped spaced apart walls b^2 and b^3 and the connecting walls b^4 and b^5 , and 70 having the open end b^6 , the outer end of each unit being trimmed to conform to the rim member of the wheel, all constructed and arranged substantially as shown and described.

5. In a wheel of the character described, 75 the supporting units each formed from a single blank and comprising the hub end base b^1 , the two spaced apart main side walls b^2 and b^3 , and the connecting walls b^4 and b^5 , substantially as set forth.

6. In a wheel of the character described, 80 the reinforcing felly member consisting of the series of unit closure sections arranged in abutting relation to form an annular 85 felly member, substantially as shown and described.

7. In a wheel of the character described, 85 as a supporting body between the hub and rim members, a plurality of hollow metal units, each made in a single piece so as to provide integrally the two sector shaped spaced apart walls b^2 and b^3 and the connecting walls b^4 and b^5 , and means for securing 90 such supporting units in the wheel structure. 100

8. A wheel comprising a suitable hub and tire carrying rim and between said hub and rim a supporting structure consisting of a plurality of metal units, each unit being 105 formed in a single piece so as to provide integrally the two sector shaped spaced apart walls b^2 and b^3 and the connecting walls b^4 and b^5 , and leaving in each the open end b^6 , and a reinforcing felly member consisting of the series of unit closure sections 110 arranged in abutting relation, substantially as set forth.

In testimony whereof, I have hereunto signed my name to this specification.

GERALD G. BARRY.
